(57) CLAIM

The ornamental design for a Christmas tree topper, as shown and described.

DESCRIPTION

FIG. 1 is a front, right, and top perspective view of a first embodiment of a Christmas tree topper, showing my new design;

FIG. 2 is a rear, left and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, right, and top perspective view of a second embodiment of a Christmas tree topper, showing my new design; and,

FIG. 10 is a rear, left and bottom perspective view of a third embodiment of a Christmas tree topper, showing my new design.

The broken lines shown in the drawings are included for the purpose of illustrating portions of the Christmas tree topper that form no part of the claimed design.

1 Claim, 10 Drawing Sheets(56)
